DIVIDER FOR A DISPLAY CONTAINER

James C. Macklem, Coldwater, Mich., assignor to Syndicate Glass Incorporated, Indianapolis, Ind.

Filed Mar. 14, 1975, Ser. No. 558,231

Term of patent 14 years

Int. Cl. D6—99

U.S. Cl. D6—85

Fig. 1

Fig. 2

Fig. 3

Fig. 4

Fig. 5

FIG. 1 is a front elevation of a divider for a display container of this invention.

FIG. 2 is a top plan view of the structure of FIG. 1.

FIG. 3 is a rear elevation of the structure of FIG. 1.

FIG. 4 is a side elevation of the structure of FIG. 1 taken looking from the left hand side of FIG. 1.

FIG. 5 is a bottom view of the structure of FIG. 1.

The side opposite to the side illustrated in FIG. 4 is the mirror image of FIG. 4.

I claim:

The ornamental design for a divider for a display container, as shown and described.
